UNITED STATES PATENT OFFICE.

WILLIAM P. HAMMOND, OF PASSAIC, NEW JERSEY, ASSIGNOR TO A. SCHRADER'S SON, INCORPORATED, OF BROOKLYN, NEW YORK, A CORPORATION OF NEW YORK.

PRESSURE-GAGE AND PUMP CONNECTION.

1,330,759.

Specification of Letters Patent.

Patented Feb. 10, 1920.

Application filed December 19, 1913, Serial No. 307,689. Renewed July 2, 1919. Serial No. 308,293.

To all whom it may concern:

Be it known that I, WILLIAM P. HAMMOND, citizen of the United States, residing at Passaic, in the county of Passaic and State of New Jersey, have invented certain new and useful Improvements in Pressure-Gages and Pump Connections, of which the following is a specification.

The present invention relates to a combination pressure gage and pump connection for fluid pressure containers such as pneumatic tires, and also to novel means for quickly and detachably connecting a pressure gage, dust cap, or like member to the valve casing of a pneumatic tire.

One of the objects of the invention is to provide a combination pressure gage and pump connection for pneumatic tires which can be quickly placed in position or removed therefrom, and which embodies novel features of construction whereby an outlet or blow-off valve is automatically opened when the pressure within the tire has been built up to the predetermined point, thereby preventing overinflation of the tire. Further features of the invention reside in the provision of means for adjusting the pressure at which the blow-off valve will be opened, and also for preventing the blow-off valve from being prematurely actuated by fluctuations in pressure from the strokes of the pump.

A further object of the invention is to provide a novel means for quickly and detachably connecting a pressure gage, dust cap or the like to the valve casing of a tire whereby the member is held securely in position although it can be quickly removed without the loss of time which is always incidental to such an operation where a threaded connection is employed.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a longitudinal sectional view through a combination pressure gage and pump connection constructed in accordance with the invention.

Fig. 2 is a side elevation of the same.

Fig. 3 is a side elevation of a slightly modified construction of the pressure gage and pump connection, showing also the upper end of the valve casing.

Corresponding and like parts are referred to in the following description and indicated in all the views of the drawing by the same reference characters.

Referring to Fig. 1 which illustrates a combined pressure gage and pump connection constructed in accordance with the invention, the numeral 1 designates the main casing which is shown as open at both ends and provided with an intermediate transverse partition 2 subdividing the casing into an upper chamber A and a lower chamber B. A cap 3 is fitted over the lower end of the casing 1, said cap having an opening 4 therein adapted to loosely receive the valve casing of a tire valve. A rubber washer member 5 fits against the upper surface of the cap 3 and is clamped between the said cap and the lower end of the casing 1, the central portion of the washer member being formed with an upwardly projecting nipple member 6 adapted to fit closely around the tire valve casing so as to produce a tight joint therewith. A tubular pump connection 7 projects laterally from one side of the casing 1 and communicates with the lower chamber B, and a valve opening pin 8 projects downwardly from the partition 2 so as to engage the valve stem of the tire valve and open the tire valve when the device is applied thereto. This valve opening pin 8 is formed with a constricted duct 9 leading from the chamber A to the chamber B whereby the said chamber A has the same internal pressure as the pneumatic tire, although it is shielded against sudden fluctuations of pressure from the pump.

A diaphragm 10 is fitted over the upper end of the casing 1 and carries an upwardly projecting valve tube 11 which is slidably mounted within the outer tubular casing 12. A central opening 13 in the diaphragm 10 communicates with the interior of the valve tube 11 while the outer end of the valve tube is closed by an inwardly opening valve 14, said valve being held yieldably upon its seat in the usual manner and being provided with a valve stem 15 projecting beyond the end of the valve tube. A fixed abutment such as a transverse pin 16 is arranged with-

in the outer end of the tubular casing 12 for engagement with the valve stem 15 to open the valve 14 and thereby release the pressure within the fluid pressure container or pneumatic tire when the pressure acts upon the diaphragm 10 with sufficient force to move the same outwardly and bring the valve stem 15 against the abutment 16.

The outer end of the valve tube 11 may be surrounded by a guide sleeve 17 which slides freely within a guide sleeve 18 fitted within the interior of the tubular casing 12. Interposed between the shoulder at the lower end of the guide sleeve 18 and the diaphragm 10 is a coil spring 19 which normally tends to move the diaphragm inwardly and resist the action of the pressure within the chamber A upon the diaphragm. The tubular casing 12 is carried by a cap 20 threaded upon the upper end of the casing 1, and it will be obvious that by screwing this cap either one way or the other the tension in the spring 19 may be increased or decreased as found desirable. As indicated by Fig. 2, the exterior of the cap 20 is provided with a knurled portion 21 adapted to be readily engaged by the fingers, and also with graduations 22 adapted to coöperate with a pointer 23 on the pump connection 7 to engage the interior pressure within the tire which must be reached before the blow-off valve 14 will be opened. With this construction it will be obvious that the operator adjusts the regulator cap 20 upon the casing 1 until the pointer 23 is opposite that indication 22 of the scale corresponding to the maximum pressure which it is desired to build up within the tire. The spring 19 will then cause the diaphragm 10 to resist the internal pressure within the chamber A until the predetermined maximum pressure is reached, at which time the outward movement of the diaphragm and valve tube 11 will be sufficient to bring the valve stem 15 into engagement with the abutment 16 and unseat the valve 14. The pressure within the tire will thus be relieved, although the valve 14 will again close as soon as the pressure falls below the predetermined pressure. One manner of securing a quick detachable connection between the pressure gage and pump connection and tire valve casing is shown by Figs. 1 and 2. This form of fastening includes a pair of opposed spring arms 25 projecting downwardly from the stock or body portion of the pressure gage and adapted to be disposed on opposite sides of the tire valve casing. In the present instance these spring arms 25 form the end portions of a spring strip of metal, the middle portion of the metal strip being riveted or otherwise permanently connected to the cap 3. The lower or free ends of the spring arms 25 carry the inwardly projecting and overlapping plates 26 which have openings

27 therein of a sufficient size to loosely receive the tire valve casing. The resiliency or spring action of the arms 25 normally holds the openings 27 out of alinement with each other or in an offset relation, although when the spring arms 25 are forced inwardly by grasping them between the fingers and applying pressure thereto in any other suitable manner the openings 27 may be brought accurately into registry so as to admit of the device being slipped over the tire valve casing. As soon as the pressure gage has been properly seated upon the end of the tire valve casing, the spring arms 25 are released and the edges of the openings 27 in the overlapping plates 26 thereby caused to grip opposite sides of the tire valve casing so as to produce an interlocking connection therewith and securely retain the device in position.

85

Having thus described the invention, what I claim as new and desire to secure by Letters Patent, is:—

1. A device of the character described including a casing having a pump connection 90 and provided with means for attachment to a tire valve casing, a diaphragm upon the casing, a blow-off valve carried by the diaphragm, a cap adjustably mounted upon the casing and carrying a shoulder, a spring 95 interposed between the shoulder and the diaphragm, the tension of the spring being regulated by adjusting the cap on the casing, and an abutment in the path of the blow-off valve for engaging and opening 100 the same when a predetermined pressure is reached.

2. A device of the character described, including a casing subdivided by a transverse partition into a valve chamber and an open 105 ended diaphragm chamber, a constricted duct being provided between the two chambers, a diaphragm stretched across the open end of the diaphragm chamber and closing the said chamber, a blow-off valve carried 110 by the diaphragm and movable therewith, an abutment arranged in the path of the blow-off valve for opening the same when a predetermined pressure is reached, an adjustable mounting for the abutment, a pump 115 connection leading to the valve chamber, and means for connecting the valve chamber to a tire valve casing.

3. A device of the character described including a casing having open ends and provided with an intermediate transverse partition subdividing the same into a diaphragm chamber and a valve chamber, a diaphragm closing the diaphragm chamber, a blow-off valve carried by the diaphragm, 125 an abutment arranged in the path of the blow-off valve for automatically opening the same when a predetermined pressure is reached, a cap closing the valve chamber and provided with an opening to receive the 130

tire valve casing, a valve opening pin projecting from the partition and arranged opposite the opening of the cap to unseat the tire valve when the device is applied thereto, a constricted duct being provided between the diaphragm chamber and the valve chamber, and a pump connection leading to the valve chamber.

4. A device of the character described including a casing subdivided by a transverse partition into a diaphragm chamber and a valve chamber, a constricted duct being provided between the two chambers, a diaphragm extending across the diaphragm chamber, a valve tube carried by the diaphragm and in communication with the diaphragm chamber, a blow-off valve within the valve tube, a tubular guide within which the valve tube slides, an abutment within the tubular guide for engaging the blow-off valve and opening the same when a predetermined pressure is reached, a cap adjustably mounted upon the main casing and

carrying the tubular guide, and a spring engaging the diaphragm and arranged to have 25 the tension thereof regulated by adjusting the cap upon the main casing.

5. An air valve comprising a casing, a diaphragm therein adapted to be acted on by air pressure, a sleeve carried by said diaphragm, adjustable means for guiding the movement of the sleeve, a compression spring acting between said guiding means and diaphragm for resisting the action of the diaphragm, a valve mechanism within 30 said sleeve, and means carried by said guiding means for engaging said valve mechanism after a predetermined displacement of said sleeve whereby the air which acts on the diaphragm is permitted to escape. 35

In testimony whereof I affix my signature in presence of two witnesses.

WILLIAM P. HAMMOND.
